DESIGN.

T. J. STEARNS.

CARPET.

No. 16,494.

Patented Jan. 26, 1886.

UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 16,494, dated January 26, 1886.

Application filed December 18, 1885. Serial No. 186,091. Term of patent 3½ years.

To all whom it may concern:

Be it known that I, THOMAS J. STEARNS, of Boston, in the county of Suffolk and State of Massachusetts, have invented a certain new 5 and original Design for Carpets, of which the following is a specification.

The nature of my design is fully shown by the accompanying photographic illustration.

The design is composed of the elongated octagonal figure with the floral ornamentation, the ornamented figure having its margin made up of short arcs of circles and partly covered with floral work, the oblong figure with indented corners partly covered by floral and foliage work, and the minor details of ornamentation, all as shown. 15

I claim—

The design for carpets, substantially as shown and described.

In testimony whereof I have signed my name 20 to this specification, in the presence of two subscribing witnesses, this 14th day of December, 1885.

THOMAS J. STEARNS.
